W. GROAT.
Car-Axle Box.

No. 12,591.

Patented March 27. 1855.

Inventor;
W. Groat

UNITED STATES PATENT OFFICE.

WARNER GROAT, OF TROY, NEW YORK.

PACKING JOURNAL-BOXES.

Specification of Letters Patent No. 12,591, dated March 27, 1855.

To all whom it may concern:

Be it known that I, WARNER GROAT, of Troy, in the county of Rensselaer and State of New York, have invented certain new and useful Improvements in the Mode of Tightening the Packing of Journal-Boxes; and I do hereby declare that the following is a full, clear, and exact description of the same, reference being had to the annexed drawings, making a part of this specification, in which—

Figure 1, is a longitudinal vertical section of the journal box through the center of the same; Fig. 2, is a cross sectional view; Fig. 15 3, is a detached view of the interior adjustable tightener; Fig. 4, is an inside view of the back end of the box, showing the permanent tightener; Fig. 5, is a detached view of the adjusting frame; Fig. 6, is a back view 20 of the journal box, with the outside adjustable tightener removed; Fig. 7, is a detached view of the exterior adjustable tightener; Fig. 8, is a view of one of the leather packing rings.

25 The same letters have reference to like parts in each of the figures.

My improvement is made on the invention patented by me the eleventh of June, 1850, where I for the first time in the history of 30 railway boxes, successfully introduced a tight packing around the axle. Many attempts at this had before been made; but in running a short time, the wear produced a leak; or if a spring was introduced to 35 prevent that result, the friction was so much increased as to produce excessive wear, heat, and deterioration, that prevented any economy or value in the use.

My improvement above alluded to has 40 effectually obviated those difficulties; but it was by its construction so difficult of access that objections on that score found to it, which my present improvement is calculated to overcome; it consists in placing the parts 45 composing the packing on the inside of the box, and in so arranging and constructing them, as to be acted on from the outside end, without removing any of the parts, or getting under the truck to adjust it; and further, by putting all the adjustments within 50 the box, I preclude the necessity of making holes through it, by which leakage of oil will occur.

The description is as follows: viz: A is 55 the journal box; B, the journal; C, the bearing (a, a) are annular packings of leather,

or other suitable material; two of the leather rings are used on the inside of the box; they are slipped over the end of the axle, and fitted up against the inside permanent tightener (b) as seen Fig. 1; the adjustable tightener D, Fig. 3, is then slipped over the end of the axle, and brought up against the packing, the flange or shoulder C, of the same, fitting closely around the lower edges 60 of the annular packing. The bottom part of the inside adjustable tightener is forked, the two legs of which, (d, d) are rounded at the ends, as seen in Fig. 1; F, is the adjusting frame lying on the inside bottom of the 70 journal box; the ends (e, e) are rounded, so as to correspond with the forks of the adjustable tightener; F is a wedge or wheel which when turned around, or driven forces the adjusting frame forward, consequently 75 drives up the adjustable tightener, so as to tighten the packing around the axle; when sufficiently tightened the braces G G are slipped in, and hold the tightener firmly on the packing.

80 The outside packing is held and adjusted as follows: Upon the outside end of the journal box is cast the permanent tightening flange or shoulder (f), as seen in Fig. 6; the adjustable outside tightener, H, Fig. 7, has 85 a corresponding flange. The outside leather packing rings, (g, g) are slipped over the journal or axle, the packing is brought up to its proper position against the permanent tightener, the adjustable tightener, which 90 had been previously over the axle, is then fitted on to it, the flange or shoulder (h) of the same, bearing against the lower edge of the packing; the tightener is then secured in proper position by means of the screws 95 (k, k) which pass through the slots (l, l) in the tightener, and screw into the journal box. The slots are for the purpose of allowing an adjusting motion to the tightener, which is tightened on the packing, so as to 100 make the same oil tight, and held in position by means of the set screw (m). The packing being adjusted, and the box supplied with oil, the lid J, is then put on and secured by means of the screw (n); the joints of the lid are made oil tight by means of packing (o).

105 It will be obvious to any experienced machinist, that the tighteners can be adjusted and held in proper position, in various ways, and by different arrangements of means for that purpose; one of these devices is shown 110

in Fig. 9, in which E is a lever, whose fulcrum is at (e'); the inner end of the lever passes under the center of the adjustable tightener D, and holds it up by the bearing 5 down of the opposite end by the eccentric on wheel F; the form of this eccentric is more clearly shown at Fig. 10. The wheel is serrated on its edge, and is held in place by the cover J; but it is impossible, especially in journal boxes for rail road trucks, 10 that no screw holes be made through that part of the box containing the oil, as the screws from the tremors and shaking consequent upon the motion of the truck, renders them very liable to become loose and fall 15 out, consequently losing the oil; the outside and inside packing can be used together, so

as to form double packing, or singly, as may be desired.

Having thus described my improvements 20 in packing journal boxes, what I claim as my invention, or improvement, is—

The combination and arrangement of the packing ring and apparatus for tightening the same within the box, substantially as described, so that the packing in the inner end of the box can be tightened at the outer end, and the box be kept oil tight without being pierced with holes, as above specified. 25

WARNER GROAT.
